CLAIM

The ornamental design for a wireless charger, as shown and described.

DESCRIPTION

FIG. 1 is a front, left, top perspective view of a wireless charger, showing my new design;

FIG. 2 is a rear, right, bottom perspective view thereof;

FIG. 3 is a rear, left, top perspective view thereof;

FIG. 4 is a front elevational view thereof;

FIG. 5 is a rear elevational view thereof;

FIG. 6 is a left side view thereof;

FIG. 7 is a right side view thereof;

FIG. 8 is a top plan view thereof;

FIG. 9 is a bottom plan view thereof;

FIG. 10 is an enlarged view of an enclosed portion of the wireless charger labeled 10 in FIG. 3; and,

FIG. 11 is an enlarged view of an enclosed portion of the wireless charger labeled 11 in FIG. 6.

The dashed broken lines in the figures are for the purposes of illustrating portions of the wireless charger and form no part of the claimed design.

The short-short-long dashed broken lines immediately adjacent to the claimed areas in the views represent the boundaries of the design and form no part of the claimed design. The dash-dot-dash broken lines enclosing portions of the wireless charger illustrated in enlargements form no part of the claimed design.
